ROTARY ENGINE

James L. Kempthorne, Montclair, N. J.

Application March 3, 1934, Serial No. 713,842

8 Claims. (Cl. 103—142)

This invention relates to improvements in pumps, engines, compressors and the like and more particularly to means for and methods of controlling the pressure of positive displacement rotary pumps. It is an improvement on the devices shown in my prior Patents No. 1,904,374, patented April 18, 1933, and No. 1,930,480, patented October 17, 1933.

I have heretofore shown a rotary type positive displacement pump construction in which a spherical segment operated as a rotor in the hemispherical or spherical casing and made possible the intake, compression and exhaust of fluid mediums. In my present invention I have improved the mechanism so that I can continuously control the pressure output rendering the pump discharge of substantially constant pressure which is necessary in certain industrial fields. I have also improved the operating characteristics by an improved abutment which has angular faces to cooperate with the rotor so that improved porting and sealing can be obtained.

One of the principal objects of my invention is to provide a variable capacity, constant pressure pump of the rotary, positive displacement type in which the pressure may be initially set at a predetermined value by any desired manual or automatic means and the discharged fluid will be under substantially constant uniform pressure regardless of capacity demand within the range of the pump.

Another object of my invention is to provide a rotary type positive displacement pump which is particularly adapted for pumping fuels and lubricants irrespective of their viscosity, so that a more exact control of the fuel or lubricant can be had and so that constant pressures with capacity variations to supply demand can be had without the usual relief valves and other regulating devices.

Another object of my invention is to provide a rotary positive displacement pump with a constant pressure control device operable from its own or other pressure sources to automatically vary the capacity in accordance with the fluctuations in the pressure source and to act, for example, as an unloading device so that the motor can come up to speed before the pump starts to work.

A further and more detailed object of the invention is to provide a better seal and porting arrangement for a constant pressure pump by making the rotor more nearly hemispherical for use of cylindrical rings and providing an abutment plate with faces in angular relation and

with a smaller port volume so that the pump has a higher volumetric efficiency and a better vacuum lift.

Another object of my invention is to provide a simple and highly effective control for reversing the flow of a pump of the rotary, positive displacement type, such control being either manual or mechanical, and which may be remotely controlled.

Further objects and advantages of my invention will appear from the following description thereof taken in connection with the attached drawings which illustrate preferred forms of embodiment to which my invention is susceptible and in which:

Figure 1 is a vertical section substantially through the center of an improved type rotary pump having a constant pressure control;

Figure 2 is an exploded perspective view of certain of the respective operating parts of the pump shown in Figure 1;

Figure 3 is a substantially central vertical section of a modified form of control showing the use of a sylphon bellows diaphragm controlling the pressure by regulating the rotor position;

Figure 4 is a partial vertical section of a further modified form of construction using a tensioning device for controlling the position of the pump rotor;

Figure 5 is a partial central vertical section of a still further modified form of construction having a dash pot control for the adjustment of the capacity of the pump;

Figure 6 is a detail vertical section showing a form of manual adjustment, and,

Figure 7 is a detailed vertical section of a still further modified form of construction showing an oil filled type of retarder for the control arm movement.

A simplified form of positive displacement rotary pump as more particularly shown in Figure 1, comprises a two-part casing 10 and 11, the part 11 having a flange 11a adapted to be secured to a supporting framework. The ported part of the casing 11 carries the drive shaft 12 to the end of which is secured the rotary abutment plate 14. The shaft 12 is journaled in suitable bearings 15 and is preferably provided with suitable fibrous packing 16 for oiling purposes. The packing is secured in position by a suitable collar 17 and an adjustment bushing 17a or in any other desired manner.

The rotary abutment plate 14 is shown in greater detail at the right in Figure 2, and is shown to have a plurality of faces 14a, which, if

continued to a central point, would be angularly disposed with respect to each other. The center of the plate however, is provided with a partially cylindrical groove 14b, to receive the cylindrical retaining member 18b hereinafter described. The faces 14a are also cut away in the center as shown at 14c to cooperate with the ports in the casing part 11.

The casing part 10 carries a hemispherical housing 19 which is held against the casing part 11. If desired these parts could be made integral. The hemispherical housing 19 receives the hemispherical rotor 18 which is substantially filled by it. The rotor is preferably provided with suitable sealing rings 18a and as the rotor is a full hemisphere, these may be cylindrical in shape.

The rotor 18 is shown in greater detail in the center of Figure 2 and is shown to have a transverse sealing member 18b which is held to the flat face of the rotor by suitable screws 18c. When the parts are assembled the rotor is driven by the abutment plate and as the rotor is held in fixed position with respect to the abutment plate 14, all reaction on the housing 19 due to pressure on the face of the rotor, is relieved. This materially reduces friction in operation. Due to the shape of the groove 14b in the rotary plate and the substantially cylindrical bar 18b the rotor may oscillate however and the porting of the face of the rotor will contact first with one angular face of the rotary abutment plate and then with the other face. This action is brought about by off-setting the rotor axis with respect to the axis of the abutment plates as hereinafter described.

The abutment plate 14 and the rotor 18 will be moved longitudinally until the rotor engages the hemispherical wall in the chamber 19 due to the action of springs 11b on the collar 11c which engages the abutment plate. The wear on the chamber and rotor walls will thus be compensated and the more the pump is operated, the better the fit will be. If desired the rotor wall may be relieved throughout a substantial part of its area to reduce wear on the respective parts.

The housing 19 carries a control arm 25 which controls the position of the rotor with respect to the relative angularity between a normal to the rotor face or the axis on which it rotates and the axis of the drive shaft and abutment plate 14. This angle directly controls the capacity of the pump for the compression chamber 31 between the faces of the abutment chamber 14 and the rotor member 18 is governed by it.

The rotor position control arm 25 is provided with suitable slots 25a which closely fit similar grooves in the hemispherical casing 19 so that there is a relatively low degree of friction and a relatively low loss of pressure. The position control arm 25 extends through a slot 19a in the hemispherical casing and on its inner end is provided with a central bore 25b to receive a detachable spindle member 26 which is keyed to the transverse bar 18b by the pin 28, the spindle 26 passing through a slot 27 in the rotor 18. It will thus be seen that movement of the rotor position control arm 25 will effectively manipulate the angularity of the rotor.

The intake to the pressure chamber is through the port 30 and due to the angularity of the rotor to the axis of the drive shaft 12, one portion of the rotor will first contact with one of the faces 14a of the abutment plate 14 to leave a space 31 between the other face 14a and the other portion

of the rotor for the reception of fluid which enters said space from point 30 through the channel 14c of the abutment plate. Upon rotation of the shaft, the sides of the abutment plate close the port 30, and the fluid within the space 31 is compressed between the rotor 18 and abutment plate 12 and discharged through channel 14c and the discharge conduit 32. Thence it passes through the conduits 33 into the intermediate pressure control chamber 34 and to the final pressure outlet 35.

The intermediate pressure control chamber 34 is preferably in the end of the cylinder 20 having the piston 21 which is held in upper position against fluid pressure by the spring 22. The piston divides the chamber and forms a gas tight portion below the piston. The piston is carried on the piston rod 24 which extends through suitable adjustable bushings to connect with the rotor position control arm 26 as by a screw joint 20 shown at 27. A relief valve 36 may extend through cylinder wall 20 into chamber 20a to relieve the chamber from any collection of liquid therein.

The automatic operation of the device is therefore as follows: The discharged fluids under pressure normally hold the piston in a position against the operation of the spring 22 thus maintaining the angular relation between the rotor and the drive shaft. If the pressure should tend to increase, however, the piston 21 would be forced downwardly to reduce the angularity and therefore reduce the capacity of the rotary pump. If the pressure should decrease as would take place with an increase of capacity demand in the pressure discharge line 35, the piston 21 would move upwardly thus increasing the angularity of the rotor and therefore increasing its capacity.

The movement of the piston may be further restricted by a certain compression below the piston 21. One or more gaskets 21a may be used, although, due to the pressure on the top of the piston, the gasket expands and acts as a seal against the gases in the lower part of the chamber as well. Adjustments may be made to initially set the tension of the spring by means of the adjustable collar 23 and the member 23a which cooperates with the spring. The control may be set for a determined pressure and the pressure will not be varied except within very small limits. The control is sensitive to changes in capacity and thus pressure is entirely automatic and simple. Any desired characteristics may be obtained by suitable selections of springs and variation in cylinder sizes as is well known. It is of course possible to omit the relief valve 36 and leave an aperture opening into chamber 20a and rely on the spring 22 to balance the pressures in chamber 34. No dash pot action would then be had.

A pump of this type is especially suitable for pumping viscous liquids as it will act to pump regular amounts of liquid irrespective of variations in viscosity. It is also suitable for fuel pumps as the pressure being constant, the capacity will be proportional to the speed and no floats, relief valves or other control means will be necessary. In automotive work this will permit the elimination of the carburetor and fuel pump and the substitution of a simple mixing valve or valves. It is also possible in such circumstances to manually control the capacity by use of levers of any desired type which may be synchronized with other valve controls or ignition controls.

In the following forms of embodiment of my

invention, I have shown slightly modified forms of rotor position control to change the position of the rotor as hereinbefore described. As the casing, rotor and rotor drive are the same or may be of any other desired construction, all the details of construction are omitted in the following figures for the sake of clarity.

The constant pressure control shown in Figure 3, includes a chamber 40 preferably of cylindrical form, having a compression chamber 41 adapted to receive the fluid discharge from the pump (not shown) or from any other source of fluid through the conduit 42, and discharging in turn, out of the main discharge conduit 43. The position control shaft is indicated at 44 and it contacts with the inside of a bellows diaphragm 45 mounted within the control chamber 40. A spring 46 is also preferably enclosed in the diaphragm 45 in order to hold the control arm 44 in a tensioned and relatively fixed position, free from any unnecessary fluctuation. The bellows diaphragm is sealed in the bottom of the casing 40 thereby making a gas tight chamber.

The initial tension of the spring 46 may be changed by varying the position of the chamber 40 with respect to the pump casing 47. An adjustment member 48 is adapted to move the chamber 40 away from or toward the pump casing 47 and this will tend to lengthen or shorten the effective length of the control shaft 44 and therefore control the relative pressure of the pump.

Pressure increases within the chamber 41 will tend to force the top of the bellows 45 downward to change and reduce the operating angle between the rotor and the abutment plate. This will control the pressure discharge due to the reduction in pump capacity. Reduction of pressure however will cause the diaphragm to move upwardly and the capacity will thus increase. The normal pressure will thus correspond to the fixed spring tension. There is no possibility of leaks with the bellows 45, and the control may thus be used where absolute sealing of the fluids under pressure is essential.

Another modified form of construction is shown in Figure 4 in which the rotor control arm 50 holds the rotor (not shown) in position under spring tension by the spring 51. A housing 53 surrounds the spring to permit free movement and the spring may be adjusted to any desired amount as by the adjustment 52. Although a coil spring is shown, it is clear that other tensioning devices could be used with substantially equivalent results.

In this construction of a single spring controlling the relative angularity of the rotor, any variations in pressure discharge will cause a movement of the control arm 50 to vary the capacity. This pressure change will be offset by the spring 51, however and the pressure delivered will be substantially constant irrespective of line fluctuations as the tension of the spring is entirely independent of any change of pressure.

A slightly modified form of uniform pressure control is shown in Figure 5. The control housing 60 is provided with a spring 64 which is carried on the spring seat 64a. The spring seat 64a is conveniently supported by bolts 64b extending to the top of the control housing 60. Other supporting means for the spring could be substituted if desired.

A spring head 69 is mounted on the upper end of the extension rod 67 which is connected to the piston rod 68 and thence to the rotor position control arm 66. The piston rod 68 carries a pis-

ton 65 which acts as a dashpot against the pressure in the pump casing 66a.

The operation of this form of embodiment depends on an increased pressure in excess of the tension of the spring which will act on the rotor (not shown) to move the spring 64 and dash pot. If due to an increased volume demand, the pressure should drop, the spring would change the rotor position to increase the capacity and keep the pressure constant. Any sudden movement however due to a change in pressure which would normally cause a sudden movement of the rotor position control arm 66 is damped by the dash pot piston 65 and the rotor moved through the proper angle in a relatively slow manner. The arrangement of connections is such that it is impossible to suddenly vary the capacity of the pump although a continuous pressure differential will effect the movement of the control arm 66. This form of construction is therefore particularly desirable for certain industrial units as close control can be obtained.

A reversible form of control is shown in Figure 6. The rotor position control arm 70 is held in any fixed position by means of an adjusting member 71 which may have a spin gear 71a thereon for rotation. The adjusting member 71 may preferably be in the form of a screw operating in lock nut 73, or it may be any other form of take up means. The adjusting member is connected to the control arm 70 by link 74 and a suitable swivel 75. The spin gear may be mechanically moved by the motor 76 and gear 77 connected in any desired manner and adjustment of the rotor arm may be facilitated. The pressure may thus be varied from a remote point in accordance with the capacity required so that the pressure will remain constant. The rotor position may also be changed beyond a center point so that the pressure is reversed, or a vacuum set up, or it may be held at the center point until the desired shaft speed has been obtained and thereafter moved to obtain the requisite pressure.

An oil controlled pressure device for a rotor of the hereinbefore described type which is simple in construction and highly effective is shown in Figure 7. This form of the device includes a modified form of rotor casing 80 which has an integrally formed hemispherical chamber to receive the rotor 81 which is driven from and cooperates with the abutment plate 82. The casing 80 has an extension housing 80a to which is secured the pressure control mechanism chamber 83. A spring 84 is mounted in this chamber and it abuts a piston 85 which in turn is carried by piston rod 86. The piston rod 86 is secured in any desired manner to the rotor position control arm 87.

The piston 85 fits loosely in the chamber 83 and is preferably provided with a series of holes 85a around its head. It also may have a gasket 85b. The chamber 83 is preferably filled with oil or other liquid and the casing extension 80a is similarly filled. The gasket 85b thus forces the oil to pass through the small holes or ports 85a in the piston and retards the operation of the piston. Changes of pressure, however will be reflected in the movement of the control arm of the rotor and the movement of the piston 85 against spring tension which may be adjusted by any desired means. As the piston movement controls the angularity of the rotor with respect to the axis of rotation of the abutment plate, the capacity of the pump is readily varied by ad-

justments of the spring 84. The spring may be set at any desired corresponding pressure and this pressure will be maintained by the pump.

The rotor and casing and control are preferably carried in the same housing and no leakage of oil is possible. Increase in pressure will hold the oil in place and the normal leakage past the rotor may be used for filling the chamber 83 or it may be filled through the filling plug 88.

10 I have therefore provided means for automatically controlling the rotor position of a positive displacement rotary pump. This controls the capacity of the pump which however, is proportional to the pressure so that by suitable 15 adjustments, the pressure of the pump may be set at any desired amount and it will remain substantially constant with the speed of the pump as all variations will be reflected to the rotor position control arm and the capacity varied to automatically 20 control the pressure. Variable characteristics may be obtained by various arrangements of springs, compression chambers, diaphragms and dash-pot constructions so that various industrial uses can be satisfied.

25 While I have shown preferred forms of embodiment of my device, I am aware that modifications may be made thereto and I therefore desire a broad interpretation of my invention within the scope and spirit of my disclosure herein and of 30 the claims appended hereinafter.

I claim:

1. A positive displacement rotary engine of the class described comprising a ported casing having a hemispherical chamber therein, a hemispherical rotor mounted in said casing, an abutment having flat faces angularly displaced with respect to each other cooperating with said rotor, means to simultaneously drive said abutment and rotor, the axis of rotation of said rotor when in normal operative position being at an angle to the axis of rotation of the abutment whereby the rotor comes into substantial contact with alternate faces of the abutment, movable means connected with the rotor and extending at an angle to the rotor axis whereby movement of the rotor axis causes linear movement of said movable means, yieldable means of predetermined strength normally holding said movable means in predetermined position but responsive to changing fluid pressure loads acting upon the cooperating faces of said engine to allow movement of said movable means and thereby of said rotor axis, said fluid pressure loads acting on the cooperating faces of said engine constituting the sole means for causing said movement of said rotor axis, and means acting on said movable means to prevent sudden movement thereof and thereby to prevent fluttering of the rotor.

2. A pump, compressor, or like mechanism comprising a casing having a hemispherical chamber therein, a hemispherical rotor mounted in the chamber, and an abutment having flat faces angularly disposed with respect to each other, said abutment closing the chamber, and having a driving shaft thereon, said faces converging toward the center whereby a diametrically disposed contact is established between the rotor and the abutment, means to rotate the rotor and lock the rotor to the abutment, including a slot in said abutment more than half round in cross section, and a cooperating cylindrical shaped projection on said rotor and means to vary the angular position of the rotor in the chamber with respect to the axis of said abutment, said means including a spindle member projecting into said rotor, a

position control arm cooperating with said spindle, constant tension means partially controlling the movement of said rotor position control arm and fluid pressure means cooperating with said constant tension means to fix the pressure volume characteristics of said mechanism. 5

3. A positive displacement rotary type engine of the class described comprising a casing having a hemispherical chamber therein, intake and exhaust ports in said casing, a hemispherical rotor mounted in said casing, an abutment cooperating with said rotor, said abutment having flat faces at an angle to each other, said faces being cut away radially of the same to form grooves extending through the sides thereof to points adjacent the casing parts, and the grooves being adapted to register alternately with the said intake and exhaust ports, means to simultaneously drive said abutment and rotor, the axis of rotation of said rotor being normally at an angle to the axis of rotation of the abutment whereby the rotor comes into substantial contact with alternate faces of the abutment, and means to secure and seal said rotor and abutment together intermediate of said faces. 10 15 20 25

4. A pump, compressor, or like mechanism comprising a casing having a chamber therein, an abutment member closing the chamber, a rotor member occupying a spherical portion of the chamber, said abutment member being cut 30 away to provide faces converging toward the center, means connecting said members diametrically at the center but permitting the angle between the axes of said members to be varied, means connected with one of said members for 35 rotating both simultaneously, intake and exhaust ports on opposite sides of the casing and a channel in each face of said abutment member extending substantially radially across the same and opening into the side thereof and adapted to 40 register alternately with said intake and exhaust ports, whereby upon rotation of said abutment member, communication is established between the chamber and the ports when the channels register with the ports and is cut off when the 45 channels are not in registry therewith.

5. A positive displacement rotary engine of the class described comprising a casing having a hemispherical chamber therein, a pair of cooperating rotatable members mounted in said 50 casing including a hemispherical rotor, an abutment having angular flat faces cooperating with said rotor and connected thereto, means to simultaneously rotate said abutment and rotor, the axis of rotation of said rotor normally being at 55 an angle to the axis of rotation of the abutment whereby the rotor comes into substantial contact with alternate faces of the abutment, a constant tension means connected with one of 60 said rotatable members and controlling the angular relation between the rotor axis and the abutment axis whereby fluctuations of pressure will cause a variation in the capacity of the engine, said constant tension means including a piston member and a piston arm extended at an 65 angle to the axis of said rotor, means to control the movement of said piston member in proportion to the direct pressure discharge of the engine, and means to maintain said rotor close to the wall of the spherical chamber and take up 70 for wear including strong spring means mounted in recesses in said casing and bearing against said abutment axially thereof whereby to force said rotor toward the wall of the spherical chamber. 75

6. A pump, compressor, or like mechanism comprising a casing having a hemispherical chamber therein, intake and discharge ports communicating with said chamber, an abutment member closing the chamber, a rotor member occupying substantially all of the chamber, said rotor and abutment members having opposing working faces in said chamber, the faces of one of said members being relatively cut away and converging toward the center, means to secure the rotor member and abutment member together to cause them to rotate together, means to rotate the abutment member thereby the rotor member, movable means connected with said rotor member to vary the angular relation of the rotor axis with reference to the axis of the abutment so that said rotor axis may assume positions on either side of said abutment axis, or a position in line therewith, and yieldable means of predetermined strength normally maintaining said angular relation varying means in a position such that the rotor axis lies in a plane at one side of said abutment axis whereby fluid is discharged by the mechanism out of said discharge port, but responsive to changing fluid pressure loads within said chamber acting on the opposing faces of the rotor and abutment members to permit movement of said rotor axis to positions in line with said abutment axis and on the other side thereof, whereby the flow of fluid out of said discharge port may be eliminated, said pressure loads acting on the opposing faces of the rotor and abutment members constituting the sole means for causing said movement of the rotor axis.

7. A pump, compressor, or like mechanism comprising a casing having a chamber which is a section of a sphere, intake and discharge ports communicating with said chamber, a partially spherical member mounted in said chamber, an abutment member cooperating with said partially spherical member to close said chamber, said partially spherical member and said abutment member having opposing working faces, the axes of said abutment member and of said partially spherical member normally having an angular relation to each other, means to rotate the abutment member and partially spherical member whereby to draw fluid into said intake port and to discharge the same through said discharge port, and means connected with one of said members to support said one member in

varied positions of axial angular adjustment with respect to the other of said members, said angular relation supporting means including a constant pressure means movable in response to changing fluid pressure loads on said working faces of aforesaid members whereby the delivered pressure of said pump remains substantially constant, said fluid pressure loads on said working faces constituting the sole means for causing the angular relation of said axes to be varied, and pressure damping means acting on said angular relation varying means to prevent the sudden operation of said angular relation varying means and thereby to prevent fluttering of the position of the variable member.

8. A positive displacement rotary type device of the class described, comprising a casing having a hemispherical chamber therein, intake and discharge ports in said casing, a hemispherical rotor mounted in said casing for rotation and linear movement therein, an abutment cooperating with said rotor, said abutment having divergent faces angularly disposed with respect to each other, means to rotate said abutment and rotor simultaneously, yieldable means of predetermined strength connected with said rotor and adapted normally to maintain the same in a predetermined linear position, so that its axis lies at an angle to the axis of the abutment and so that, upon rotation, the rotor comes substantially into contact with alternate faces of the abutment, said yieldable means including a rod connected with said rotor at an angle to the axis of the rotor, a piston on said rod, a housing surrounding said piston and a portion of said rod, spring means in said housing and cooperating with said piston and rod normally to maintain the same in said predetermined position, but yieldable under the influence of changing fluid pressure loads acting on the substantially contacting surfaces of the rotor and the abutment in said chamber to permit linear movement of said rotor whereby to vary the capacity of the device in accordance with such changing loads, said changing fluid pressure loads acting on the said surfaces of the rotor and the abutment constituting the sole means for causing said linear movement of said rotor, and fluid pressure damping means in said housing cooperating with said piston to prevent sudden movements of the same and said rod.

JAMES L. KEMPTHORNE.
